UNITED STATES PATENT OFFICE.

FLOYD C. STEPHENS, OF BUFFALO, NEW YORK, ASSIGNOR TO THE WITTEMAN COMPANY, OF BUFFALO, NEW YORK.

DRYING APPARATUS.

1,408,483.

Specification of Letters Patent.

Patented Mar. 7, 1922.

Application filed May 14, 1918. Serial No. 234,494.

To all whom it may concern:

Be it known that I, FLOYD C. STEPHENS, a citizen of the United States, residing at Buffalo, in the county of Erie and State of New York, have invented a new and useful Improvement in Drying Apparatus, of which the following is a specification.

This invention relates to drying or desiccating apparatus of the kind having a rotary member or members which are coated with the material to be dried and from which the dry powder is scraped.

The objects of the invention are to provide an apparatus of this kind in which two co-operating drums are so arranged as to form a part of a receptacle for the material to be dried and in which means of improved construction are employed for forming a water-tight connection between the drums and the walls of the receptacle; also to provide an apparatus of this kind in which the receptacles for the dried material are arranged at the sides of the apparatus; also to provide the drying drums with means of improved construction for removing condensed water therefrom; also to provide the float chamber of an apparatus of this kind with means for heating the material to ensure the free flowing thereof; also to improve the construction of apparatus of this kind in other respects hereinafter specified.

In the accompanying drawings:

Fig. 1 is a side elevation, partly broken away, of a drying apparatus embodying the invention.

Fig. 2 is an end elevation thereof showing the feed end.

Fig. 3 is a transverse section of one of the drying drums showing the means for removing condensed water from the drum.

Fig. 4 is an end elevation of the drying apparatus, partly in section, showing the other end of the apparatus, on an enlarged scale.

Fig. 5 is a fragmentary sectional view thereof on line 5—5, Fig. 4, showing the packing for making a substantially water-tight connection between the walls of the receptacle for the material to be dried and the drying drums.

Fig. 6 is a fragmentary end elevation of the apparatus showing the means for adjusting the packing means shown in Fig. 5.

The apparatus shown in the drawings is primarily intended for drying brewers' yeast, which is usually in a liquid, semi-liquid or semi-gelatinous form and which must be heated to a temperature at which the yeast is rendered inactive. In the construction shown, the drying drums are heated and form a part of the receptacle for the yeast to be dried, thus serving the purpose of heating the yeast in the receptacle and drying the same when it is coated on the drums. It will be understood, however, that the apparatus is not limited to be used in connection with the drying of yeast, but can be used for other purposes.

The frame of the apparatus is of suitable construction, that shown including two frame members A which are suitably connected by longitudinal tie rods or the like a. The frame members A are provided with bearings a' a² for two drying drums B B' which extend longitudinally of the apparatus and are arranged with their cylindrical surfaces in contact or in such close proximity to each other as to form the bottom of a container for the material to be dried. This container is provided with longitudinal side walls C and with end walls D which have substantially water-tight connections with the revolving surfaces of the drums B B'. The lower edges of the side walls C for this purpose are provided with suitable flexible strips c which may be made of felt or other suitable material and which engage the cylindrical surfaces of the drying drums.

The end walls D are provided at their lower edges with packing means adapted to engage the cylindrical surfaces of the drums and which are adjustable so that the packing may at all times be kept tight. In the construction shown for this purpose, a substantially V-shaped packing member d is provided which is made in two arc-shaped parts or sections meeting at the apex of the V-shaped member and conforming substantially with the peripheries of the drying drums. Each of the parts of the packing member is provided with a packing strip d' of Babbitt or other suitable material which is adapted to be pressed against the periphery of a drum so as to form a water-tight connection. The parts of each

packing member are adapted to be pressed into their operative positions by means of a plurality of bolts or screws d^2 extending through flanges or projections d^3 formed on the end wall D. After a packing member d has been adjusted as desired, relatively to the drums B, it is secured in the adjusted position by means of a plurality of screws or bolts d^4 which clamp the packing member against the end wall D. As the packing strip d' wears out, the bolts d^2 can be tightened so as to take up the wear and in this manner the joints between the end walls D and the drums can at all times be maintained tight. When Babbitt or other soft metal packing is used in a joint of this kind, a water-tight connection can be formed between the end walls and the peripheral surface of the drums and a good bearing surface is also formed between the packing and the drums which produces very little friction.

The drying drums rotate in the direction indicated by the arrows in Fig. 4, and the peripheries thereof are coated while in contact with the material in the receptacle. The material is dried on the surface of the drums while passing from the receptacle to scraping members or knives E which, in the construction shown, are mounted on suitable holders e having arms e' engaged by adjusting screws e^2 by means of which the knives can be adjusted relatively to the drums. The adjusting screws e^2 are arranged on brackets e^3 extending outwardly from knife-supporting frames e^4 secured to the side walls C. The knives E may be of any suitable construction and extend lengthwise throughout the length of the drums. The material scraped from the drums by the knives falls upon inclined plates or chutes e^5 which direct the dried material into troughs or conveyer housings F arranged at opposite sides of the apparatus beyond the sides of the drying drums. The material may be removed from the troughs F in any suitable manner, for example by means of screw conveyers f arranged in the troughs and which move the dried material to the ends of the troughs where it may be collected by any suitable means, not shown. The screw conveyers also serve the purpose of breaking up the dried material if the same is scraped from the rolls in the form of flakes. The inclined plates or chutes e^5 extend over the edges of a drip pan or receiver f' which may be of any suitable construction and which is arranged below the driving drums so as to receive any wet material which may drop from the drums or which may leak out of the receptacle for the material to be dried. By means of the construction shown, no wet or moist material can become mixed with the dried material.

The receptacle for the material to be dried is provided with an upper extension or boiling box G which is suitably secured to the walls of the receptacle and forms an extension thereof. This boiling box prevents the material from boiling over and when the apparatus is used for drying yeast, the foam formed during the heating of the yeast is confined in the boiling box. The boiling box is provided with the usual flue or exhaust pipe g by means of which the steam or vapor is withdrawn from the boiling box, and an overflow pipe g' is also preferably provided which is adapted to prevent the overflow of the receptacle and which terminates at its lower end in the drip pan f'. The exhaust pipe g is provided with a branch g^2 extending down into the drip pan f' to withdraw moisture therefrom and from the surfaces of the drying drums. The boiling box is provided with usual hinged covers or lids g^3 .

The drying drums in the construction shown are heated by steam which is supplied to the drums by means of a steam pipe h having branches leading to each drum, each branch terminating in a pipe fitting H having a central steam supply pipe h' secured thereto in such a manner as to receive the steam from the pipe h . Each of the steam supply pipes h' extends through a hollow rotary trunnion or stud shaft h^2 of the corresponding drying drum and terminates in the interior of the drum. The pipe h' is of smaller diameter than the internal diameter of the shaft h^2 of the drum so that an annular passage is formed between the rotary shaft and the fixed steam supply pipe, through which condensed water or steam may be discharged from the drying drum. h^3 represents a gland connecting the stationary pipe fitting H and the rotary shaft h^2 . A pipe h^4 connects with the pipe fitting H to withdraw the condensed water and to discharge the same to a steam trap h^5 . Any other means for supplying steam to the drying drums may be provided.

The following means are preferably provided for discharging the condensed water from the steam drums into the annular passages in the stud shafts h^2 . The stud shaft of each drying drum is provided with an extension or part I having a lateral arm i to which a water scoop K is secured. The scoop K has an outer portion or wall k which is substantially of the same curvature as the periphery of the drying drum and is arranged in close proximity thereto. The scoop has an opening k' facing the direction of rotation of the scoop and drying drum, through which the water may enter into the scoop. The scoop is fixed relatively to the drum, so that when the scoop and drum rotate, the water will pass into a pipe k^2 connecting the scoop with the part I, causing

the water to flow through the hollow shaft h^2 . The fact that the scoop is raised above the level of the shaft h^2 increases the head of water therein so as to ensure the discharge of the same to the steam trap. Since the scoop rotates with the drying drum, there are no contacting surfaces between the drum and the scoop and the water is substantially continuously removed from

10 the drum.

The drying drums may be driven in any suitable manner, for example by means of worms L suitably mounted on a driving shaft l and engaging worm gears l^1 , Fig. 1, 15 secured on the stud shafts h^2 of the driving drums. Sprocket wheels l^2 are mounted on the stud shafts h^2 and are connected by means of chains to sprocket gears l^3 mounted on the shafts of the conveyers f .

20 When the apparatus is used in connection with a thick liquid, such for example as yeast, it is desirable to provide means for heating the liquid fed to the apparatus to ensure a continuous flow thereof. In the 25 construction shown, a float chamber or regulating device M is provided for maintaining a substantially constant level of liquid in the receptacle for the material to be dried, and it may be of any desired construction.

30 The float chamber, in the construction shown, is provided with jacketed walls m to which exhaust water or steam is supplied from the steam trap through a pipe m' so that the proper operation of the float chamber is ensured without excessive heating of the material in the float chamber. The water may be discharged from the jacketed walls by means of a discharge pipe m^2 . By heating the float chamber, a constant supply 35 of material to the apparatus is assured, as well as the accurate control of the level of liquid in the apparatus.

The apparatus described has the advantage of being thoroughly reliable in operation and assuring a thoroughly uniform coating of the drying drums. The arrangement of the troughs or conveyer housings at the sides of the apparatus positively prevents any moist or wet material from 40 coming mixed with the dry material, which is particularly important when the apparatus is used for drying yeast, since a small quantity of wet yeast will spoil a large quantity of dry yeast if mixed therewith. The construction of the container for the material to be dried as described ensures a water-tight structure which is essential to the successful operation of the apparatus. The water scoop described quickly removes 45 water from the drying drums and therefore keeps these drums operating at their highest efficiency. By means of the arrangement of the steam and condensed water connections described, all the steam and water piping 50 is arranged at one end of the apparatus and

the dried material is discharged at the other end. This structure adapts the apparatus particularly well for the arrangement of two of the drying apparatuses endwise with regard to each other, so that all the dried material can be discharged into a single receptacle and also avoids all possibility of having moisture from the steam and water connections spoil the dried material.

I claim as my invention:

1. In a drying apparatus, the combination of a pair of drying drums arranged in close proximity to each other and forming a bottom of a receptacle for the material to be dried, side walls and end walls for said receptacle, arc-shaped packing members movably mounted on said end walls and adapted to engage the curved peripheries of said drums, and means for adjusting said packing members toward and from said drums relatively to said end walls.

2. In a drying apparatus, the combination of a pair of drying drums arranged in close proximity to each other and forming a bottom of a receptacle for the material to be dried, arc shaped end walls for said receptacle, metallic packing members movably mounted on said end walls and adapted to engage the cylindrical surfaces of said drums, and pressure devices arranged on said end walls for engaging said packing members relatively to said cylindrical surfaces to make a tight joint.

3. In a drying apparatus, the combination of a pair of drying drums arranged in close proximity to each other and forming a bottom of a receptacle for the material to be dried, arc shaped end walls for said receptacle, metallic packing members movably mounted on said walls and adapted to engage the cylindrical surfaces of said drums, pressure devices arranged on said end walls for engaging said packing members at intervals for adjusting portions of said packing members relatively to said drums, and means for clamping said packing members against said end walls to hold the same in their adjusted positions.

4. In a drying apparatus, the combination of a pair of drying drums arranged in close proximity to each other and forming a bottom of a receptacle for the material to be dried, side walls and end walls for said receptacles, arc shaped metallic packing members movably mounted on said end walls and extending circumferentially of said drums, means mounted on said end walls for adjusting said packing members toward and from said drums, and means for clamping said packing members to said end walls to hold the same in their adjusted positions.

5. In a drying apparatus, the combination of a pair of drying drums arranged in close proximity to each other and forming a bottom of a receptacle for the material to be

dried, side walls and end walls for said receptacle, arc shaped metallic packing members movably mounted on said end walls, and extending circumferentially of said drums, packing strips of bearing metal on said packing members and engaging said drums, and adjusting devices arranged at intervals on said end walls and engaging

said packing members for adjusting the same relatively to said drums. 10

Witness my hand, this 7th day of May, 1918.
